UNITED STATES PATENT OFFICE.

JOHN PINTEN, OF DETROIT, MICHIGAN.

DISPLAY CABINET.

Application filed May 4, 1925. Serial No. 27,960.

This invention relates generally to display cabinets and refers more particularly to those designed for displaying seed packages and the like.

5 One of the essential objects of the invention is to provide a convertible seed box that will afford a maximum display in a minimum space on a counter or other suitable support. Another object is to provide a 10 simple and effective connection between one of the display sections and the box cover for supporting the latter in upright position.

A further object is to provide the front wall of the box with a hinged section having a shelf which is adapted to support seed packages for display purposes when the section is in open position and acts as a reinforcement for the box when in closed position.

20 Still another object is to provide a plurality of display sections which may be stored within the box for shipment and that may be readily removed and supported upon the box for display purposes.

25 With the above and other objects in view the invention consists of certain novel features of construction, combination, and arrangement of parts, as will be more fully described and particularly pointed out in 30 the appended claims.

In the accompanying drawing:

Figure 1 is a front elevation of the cabinet in open position.

Figure 2 is a view thereof in closed position.

Figure 3 is a sectional view taken on the line 3—3 of Figure 1.

Figure 4 is a detail view of the means for fastening the cover of the box in closed position.

Figure 5 is a sectional view taken on the lines 5—5 of Figure 3.

Referring now to the drawing the numeral 1 designates a box embodying my invention having the rigid bottom, back and side walls 2, 3 and 4 respectively, the sectional front wall 5, and the hinged cover 6. As shown, the lower section 7 of the front wall is rigidly secured to the bottom and side walls 2 and 4 respectively, while the upper section 8 is preferably hinged to the lower section 7 and is provided at its upper edge and with an upwardly and inwardly inclined flange portion 9. When the upper section 8 is closed, this flange 9 seats upon suitable downwardly inclined portions 10 of

the side walls 4. When in open position, the flange 9 constitutes a shelf for supporting seed packages or other articles for display. Any suitable means such as the screws 11 60 may be used to hold the cover 6 in closed position. As shown, these screws 11 preferably pass through the restricted portions 12 of wire loops 13 hingedly secured to the cover 6 and threadedly engage suitable 65 blocks 14 anchored upon the flange 9. To provide a neat joint, these blocks 14 are preferably recessed to receive the loops 13.

In order that a maximum display may be obtained in a minimum space, I preferably 70 provide two interchangeable sections or trays 15 and 16 respectively which are adapted to fit within the box for shipment and are adapted to be supported by the box for display purposes. As shown, both trays 15 and 16 are provided with the rigid bottom, back, 75 sides and front walls 17, 18, 19 and 20 respectively, however the tray 16 preferably contains a stepped shelf 21 for supporting the seed envelopes (not shown). Any suitable means such as the wire loops 22 and stays 23 may be used to divide the tray 16 80 into compartments of the desired sizes for receiving the said packages or envelopes. Inasmuch as the trays 15 and 16 are similar 85 in shape they are readily interchangeable as desired.

In use, the tray 16 containing the shelf is preferably supported upon suitable strips 24 secured to the inner faces of the side 90 walls 4 of the box, while the tray 15 is preferably supported upon the adjacent edges 25 of the section 7 of the front wall of the box so that the rear wall 18 of the tray 15 rests against the front wall 20 of the tray 16 95 as shown in Figure 1 of the drawing. Thus the space within the box below the trays may be used for storage purposes, while the seed envelopes or other articles are on display in the trays 15 and 16 respectively. 100

In order that the cover 6 may be held in raised position while the trays 15 and 16 are supported for display purposes, I preferably provide a plate 27 that is secured to the back 18 of the tray 16 so that it may fit 105 within a suitable loop 28 anchored upon the inner face of the cover 6 as shown in Figure 3 of the drawing.

In use, the plate 27 is engaged with the loop 28 preliminary to positioning the tray 110 16 upon the strips 24, whereupon the tray 16 will hold the cover 6 in raised position.

From the foregoing description it will be readily apparent that I have provided a very simple and practical box which may be readily converted into a display cabinet. It will also be apparent that this construction affords a maximum display in a minimum space, thus it is especially adapted for use upon counters and the like. Moreover this box makes an ideal shipping container.

10 While it is believed that from the foregoing description the nature and advantages of the invention will be readily apparent, I desire to have it understood that I do not limit myself to what is herein 15 shown and described and that such changes may be resorted to when desired as fall within the scope of what is claimed.

What I claim as my invention is:

1. In a display cabinet, the combination 20 with a plurality of display trays, of a box having means for housing said trays for shipment and having means rigidly secured to its sides for supporting said trays in stepped relation for display purposes, the 25 said supporting means being so arranged with respect to the walls of the box as to permit the said trays to be moved forwardly free of the said means and subsequently past the said means to a position within the box.

2. In a display cabinet, the combination 30 with a tray for holding articles on display, of a box adapted to receive said tray for shipment having means rigid with its sides for supporting said tray for display purposes, the said tray being adapted to be 35 freed from the said supporting means when positioned within the box for shipment.

3. In a display cabinet, the combination 40 with a box having spaced end walls, of a tray for holding articles on display, and means rigidly carried by said walls for supporting said tray, the said means permitting positioning of the tray therebeneath and within the box.

4. In a display cabinet, the combination 45 with a plurality of trays for holding articles on display, of a box adapted to receive said trays having means on the end walls thereof, for supporting one of said trays and having 50 means for supporting the other tray so that the rear wall thereof will rest against the front wall of the first mentioned tray, the said means permitting positioning of the trays within the cabinet and beneath the said means.

55 In testimony whereof I affix my signature.

JOHN PINTEN.
